(No Model.)

J. J. MONAHAN.

BOX FASTENER.

No. 349,514.

Patented Sept. 21, 1886.

UNITED STATES PATENT OFFICE.

JOSEPH J. MONAHAN, OF MILWAUKEE, WISCONSIN.

BOX-FASTENER.

SPECIFICATION forming part of Letters Patent No. 349,514, dated September 21, 1886.

Application filed May 17, 1886. Serial No. 202,421. (No model.)

To all whom it may concern:

Be it known that I, JOSEPH J. MONAHAN, of Milwaukee, in the county of Milwaukee, and in the State of Wisconsin, have invented certain new and useful Improvements in Box-Fasteners; and I do hereby declare that the following is a full, clear, and exact description thereof.

My invention relates to box-fasteners; and it consists in certain peculiarities of construction, as will be hereinafter described with reference to the accompanying drawings, in which—

Figure 1 represents a perspective view of a box with my invention centrally applied thereto; Fig. 2, a longitudinal section of a portion of Fig. 1; Fig. 3, an enlarged detail sectional view; Fig. 4, a perspective detail of the lock-plate and its attachments; Fig. 5, a longitudinal section of a box illustrating another form of my device; Fig. 6, a transverse section of Fig. 5, and Fig. 7, a sectional view, showing still another form of my device.

Referring by letter to the drawings, A represents the body of a box, and B the lid thereof.

In one form of my invention the box-body A is provided near its top with a transverse brace, C, having secured thereto, preferably in the center, an arrow-headed tongue, D. This tongue, in one form of my invention, has a screw-threaded shank, a, that forms the medium for securing the same to the transverse brace C, though it is obvious that said tongue may be formed with a plate, b, having perforations for screws c, as illustrated in other forms of my invention, (shown by Figs. 5, 6, and 7,) to be hereinafter described.

The box-lid B has an aperture, d, and secured to the under side of this lid is a transverse cleat, E, that is also provided with an aperture, e. Interposed between the lid B and cleat E is a plate, F, preferably provided with depending points f, that impinge the cleat to prevent dislocation of said plate, though it is obvious that other means may be employed for a like purpose.

Pivotedly connected to the plate F are fingers G, that extend up and down in the respective apertures d e of the lid and cleat, so as to be inclosed and out of the way. The lower ends of these fingers are beveled and

have shoulders g, designed to automatically engage the arrow-headed tongue D when said lid is placed in position on the box-body A.

Hinged to the top of the plate F, at right angles to the fingers G, is a gravity-latch, H, designed when closed down to come between the upper ends of said fingers, to thus retain the lower ends thereof in their engagement with the arrow-headed tongue D. The upper ends of the fingers G are each provided with a slot, h, or perforation and through these openings are passed a flexible strip, I, designed to come over the latch H, and have its ends united by suitable seal, K, as shown by Fig. 2, and over the aperture d in the lid B it is intended to place a paper seal or stamp when the box is packed, fastened, and ready for shipment.

To automatically disengage the fingers G from the tongue D when the latch H is raised, I provide said tongue with springs i, that exert their force in an outward direction, this construction being illustrated by Fig. 3.

In Figs. 5, 6, and 7 I show the part D as having a plate, b, secured by screws c to an inner side of the box-body A, and the transverse brace C entirely omitted. As shown by Fig. 6, in this form of my invention I provide the transverse cleat E on the lid B with dowel-pins k, that engage corresponding recesses, m, in an adjacent side of the box-body A opposite the tongue D, when said lid is placed in its closed position. The dowel-pins serve not only to bring the fastening mechanism into register, but also act in themselves as a means for securely fastening that side of the box-lid from which they project. In place of the dowels I may employ hinges, as illustrated in dotted lines, same figure.

In Fig. 7 I show the tongue D as having but one shoulder, and the lower portion of one of the fingers G accordingly omitted, this construction serving to somewhat cheapen the device.

Having thus fully described my invention, what I claim as new, and desire to secure by Letters Patent, is—

1. A box-body provided with a stationary tongue, the lid provided with pivoted fingers that automatically engage the tongue, and a gravity-latch hinged to said lid and arranged

to fall between the fingers when the above-named engagement takes place, as set forth.

2. A box-body provided with a tongue, the lid provided with pivoted fingers to engage said tongue, and a latch adapted to be interposed between said fingers, in combination with a flexible strip passed through the fingers over the latch and united at its ends by a suitable seal, as set forth.

10 3. A box-body provided with an arrow-headed tongue, having springs attached thereto, and the box-lid provided with pivoted fingers shouldered at their lower ends to engage the tongue, and a latch designed to be interposed between the upper ends of the fingers, as set forth.

15 4. A box-body provided with an arrow-shaped tongue, the box-lid having a cleat up-

on its under side, and these latter parts provided with apertures, in combination with a 20 suitable plate interposed between the lid and cleat, and having pivoted thereto fingers that extend up and down in the apertures of these latter parts, and are shouldered at their lower ends to engage the tongue, and a latch hinged 25 to the plate to be interposed between the upper ends of said fingers, substantially as set forth.

In testimony that I claim the foregoing I have hereunto set my hand, at Milwaukee, in 30 the county of Milwaukee and State of Wisconsin, in the presence of two witnesses.

JOSEPH J. MONAHAN.

Witnesses:

H. G. UNDERWOOD,
MAURICE F. FREAR.
